UNITED STATES PATENT OFFICE.

SAM GOLDFADEN, OF NEW YORK, N. Y., ASSIGNOR OF ONE-HALF TO
VICTOR NIVOIS, OF BROOKLYN, NEW YORK.

STOP-WATCH.

SPECIFICATION forming part of Letters Patent No. 690,721, dated January 7, 1902.

Application filed March 30, 1901. Serial No. 53,636. (No model.)

To all whom it may concern:

Be it known that I, SAM GOLDFADEN, a citizen of the United States, and a resident of the city of New York, borough of Manhattan, in 5 the county and State of New York, have invented certain new and useful Improvements in Stop-Watches, of which the following is a full, clear, and exact description.

My invention relates to watches, and has 10 for its object to provide a construction by which a so-called "start, stop, and fly-back seconds-hand" may be readily fitted to time-keeping watches, thus adapting such watches for timing horses at races and for like purposes. In explanation I would state that a 15 start, stop, and fly-back seconds-hand is one which may be allowed to be driven by the clockwork like an ordinary seconds-hand as long as desired, but upon moving a knob or 20 other operating part the seconds-hand will be stopped, and upon again moving said knob the seconds-hand will be instantly thrown back to a predetermined initial position.

The object of my invention is to provide a 25 simple construction of this character consisting of very few parts and adapted for attachment to ordinary watches, even of the cheapest grades, thus adding a valuable feature to such watches at a slight expense.

The invention will be fully described hereinafter and the features of novelty pointed out in the appended claims.

Reference is to be had to the accompanying drawings, forming a part of this specification, 35 in which similar characters of reference indicate corresponding parts in all the figures.

Figure 1 is a plan view of my improvement applied to a watch in which the seconds-hand rotates about the same axis as the hour-hand 40 and the minute-hand. Fig. 2 is a sectional elevation substantially on the line 2 2 of Fig. 1. Fig. 3 is a plan showing the improvement applied to a watch in which the seconds-hand, as usual, rotates about an axis eccentric to 45 that of the other hands. Fig. 4 is a sectional elevation substantially on the line 4 4 of Fig. 3. Fig. 5 is a partial outside view of the watch-case, and Fig. 6 is a detail view of a heart-cam and its connection with the seconds-hand 50 spindle.

In all the views many of the usual parts of

the clockwork have been omitted for the sake of clearness, it being understood that my invention has no reference to the clockwork proper, which may be of any approved construction. 55

In the arrangement shown in Figs. 1 and 2, A is the spindle of the seconds-hand A', which spindle extends loosely through the minute-hand spindle B and the latter through the hour-hand spindle C. This is an ordinary construction. As generally made, the wheel A², by means of which the spindle A is driven from the clockwork, is rigid upon said spindle. For the purpose of my invention, however, a loose wheel is employed, so that it becomes possible for the spindle A to turn backward while the wheel A² remains stationary. Normally the spindle (with the seconds-hand) and the wheel A² rotate together, this result 70 being due to the action of a spring D, coiled on the spindle and pressing the wheel A² into frictional engagement with a cross-pin or projection A³, rigid upon the spindle. This friction is sufficient to compel the spindle and 75 wheel to rotate together under ordinary circumstances, but is not sufficient to prevent a return of the spindle alone (without affecting the wheel) under the action of the fly-back mechanism to be described presently. 80

With the spindle A is held to rotate a heart-cam E, secured, for instance, by means of a cross-pin F, passing through the spindle and through lugs E' on the cam E, as shown best in Fig. 6. This cam is adapted to be 85 engaged by a knife-edge or wedge G' upon an arm G, fulcrumed at G² upon the clock-work-frame H. A spring I, secured to said frame at I' and bearing against a lug G³ on the arm or lever G, has a tendency to throw 90 the edge G' inward—that is, toward the cam E. To hold the arm G in an outer position, I provide a link J, pivotally connected with the arm G at J' and having at its other end an L-shaped slot J², in which is received a 95 guide pin or screw K, projected from the frame H. This link is further provided with two projecting pins J³ J⁴, adapted to be engaged by inclined surfaces L' L², respectively, upon an operating-arm L, fulcrumed on the frame H at L³ and having a portion L⁴ projected outwardly, preferably through the 100

watchcase M, so that the operating-arm may be readily manipulated. Further, the arm L carries a pin L⁵, arranged to engage the balance-wheel N before the link J is released 5 to allow the edge G' to move into engagement with the cam E, so as to first stop the works. The pin L⁵ is elastic, so as to enable it to yield and become bent as the arm L is moved farther. The arm L has some play between 10 the pins J³ J⁴, so that at first the arm L will move alone.

With the parts of my attachment in their outer position the clockwork is free to operate and the spindle A is free to turn with 15 the driving-wheel A². The seconds-hand and the watch will therefore go in the ordinary way. When the watch is to be used for timing purposes, as at a race-track, the operating-arm L is first swung outward fully, so 20 that first the works will be stopped by the pin L⁵ engaging the balance-wheel N, and then the incline L' by engaging the pin J³ will shift the link J until the screw K lies in the longitudinal portion of the slot J². Then 25 the spring I will suddenly throw the arm G (with the link J) inward, bringing the edge G' against the periphery of the cam E, and whatever position the cam may be in it will be thrown back instantly into such a position 30 that the edge G' will lie in the corner of the cam. In this position the cam will be held as long as the arm G remains pressed inward, and the spindle A, with the seconds-hand A', will therefore be kept stationary in a pre- 35 determined position, preferably with the seconds-hand pointing to "60" or to "XII," as the dial may be numbered. Now at the moment of the start the owner of the watch presses the arm L inward, so that the pin J⁴ 40 is engaged by the incline L², and the link J and arm G are moved outward, releasing the cam E and spindle A and at the same time setting the clockwork free, since the pin L⁵ moves off the balance-wheel N. The watch 45 will thus start, and the owner only has to follow the horse, motor-carriage, or other racer. At the finish the arm L is moved outward, but only half-way, so as to only bring the pin L⁵ against the balance-wheel without changing 50 the position of the link J. The works will therefore be arrested and the seconds-hand will stop at whatever point it may be at the moment of the finish, thus enabling the exact time to be read off. Then the 55 owner brings the arm L to its outermost position, thus allowing the link J and arm G to fly inward and bringing the seconds-hand back to its starting position, as above described. To enable the arm L to be moved 60 readily only half-way, said arm is preferably made elastic, so that it will snap into a notch H' of the case when at the center of its course and into a notch H² when at the outer end of its course.

65 When the spindle a of the seconds-hand a' has the usual eccentric location, as shown in Figs. 3 and 4, the construction is but slightly

different from that above described. The wheel a² is fast on the spindle a; but the seconds-hand a' is loose thereon, being secured to 70 a sleeve a³, rigid with the heart-cam e, and this cam has a lug e', with a spring d attached thereto, said spring engaging an angular portion of the spindle a and extending through an opening in the side of the sleeve a³. The 75 arm g, with its edge g' and fulcrum g², the spring i, the link j, with its slot j², connection j', and pins j³ j⁴, the screw k, and the operating-arm l, with inclined surfaces l' l², fulcrum l³, manipulating portion or handle l⁴, and stop-pin l⁵ are of substantially the same construction as the correspondingly lettered parts in Figs. 1 and 2, and it will therefore be unnecessary to describe them again in detail. The pin L⁵ or l⁵ may be arranged to 85 stop the balance-wheel at the same time the edge G' throws the seconds-hand back. In this case the notches H' H² are superfluous; but the seconds-hand can only be made to fly back and not to stop at the point at which it momentarily is.

I may omit the projection or pin L⁵ or l⁵, in which case the seconds-hand A' a' would fly back to its original position whenever desired, while the clockwork would continue to 95 work even when the seconds-hand is held stationary. Instead of the heart-cam I may employ a cam of an equivalent shape.

Having thus described my invention, I claim as new and desire to secure by Letters 100 Patent—

1. In a watch, the combination of a driving-wheel, a seconds-hand loosely connected therewith, a friction connection or clutch between the wheel and the seconds-hand, a heart-cam 105 rigid with the seconds-hand, a spring-pressed arm arranged to strike said cam to cause the seconds-hand to fly back to a predetermined position, a projection or stop for engaging the watch-movement to stop the same, and an operating-arm having a step-by-step movement in one direction, said arm being arranged to move the projection or stop on its initial or first step into engagement with the watch-movement and to bring about the 110 operative movement of the spring-pressed arm during the second step, the return movement of the said arm serving to disengage the projection or stop from the watch-movement and the spring-pressed arm from the cam. 115

2. In a watch, the combination of a driving-wheel, a seconds-hand loosely connected therewith, a friction connection or clutch between the wheel and the seconds-hand, a heart-cam 120 rigid with the seconds-hand, a spring-pressed arm arranged to strike the cam to cause the seconds-hand to fly back to a predetermined position, an elastic projection or stop for engaging the watch-movement to stop the same, and an operating-arm having a step-by-step movement in one direction, said arm being arranged to move the projection or stop on its initial or first step into engagement with the watch-movement and to bring about the 125

operative movement of the spring-pressed arm during the second step, the return movement of the said arm serving to disengage the projection or stop from the watch-movement, 5 and the spring-pressed arm from the cam.

3. In a watch, the combination of a driving-wheel, a seconds-hand loosely connected therewith, a friction connection or clutch between the wheel and the seconds-hand, a heart-cam rigid with the seconds-hand, a spring-pressed arm arranged to strike said cam to cause the seconds-hand to fly back to a predetermined position, a retaining-link arranged to hold said arm away from the cam, an operating-arm arranged to release said link and to bring it into the locking position, said operating-arm being capable of an independent initial movement during which it does not affect said spring-pressed arm, and a projection or stop arranged to be shifted by the initial movement of the operating-arm against the clockwork, to arrest the latter and stop the seconds-hand in the position it momentarily occupies.

4. In a watch, the combination of a driving-wheel, a seconds-hand having a friction or clutch connection therewith, an operating-arm having a two-step movement in one direction, a stop mechanism arranged to be actuated by the initial or first step of the operating-arm's movement to stop the seconds-hand, and a fly-back mechanism arranged to be actuated by the second or final step of the operating-arm's movement, the return movement of the operating-arm serving to release the seconds-hand from the action of the fly-back mechanism and of the stop mechanism.

5. In a watch, the combination of a driving-wheel, a seconds-hand loose thereon, a friction or connection or clutch between the driving-wheel and the seconds-hand, a heart-cam rigid with the seconds-hand, a spring-pressed arm adapted to strike said cam, a link having a pivotal connection with the said arm and an

45 L-shaped guideway, a stationary pin engaging said guideway, and an operating-arm having an actuating connection with said link.

6. In a watch, the combination of a driving-wheel, a seconds-hand having a friction or clutch connection therewith, an operating-arm having a two-step movement in one direction, a stop arranged to be shifted against the clockwork by the initial or first step of the operating-arm's movement, and a fly-back mechanism arranged to be actuated by the second or final step of the operating-arm's movement, the return movement of the operating-arm serving to release the seconds-hand from the action of the fly-back mechanism, 55 and the clockwork from the action of the stop.

7. In a watch, the combination with a seconds-hand mounted to be turned by the watch-movement or to turn independently thereof, and a fly-back mechanism for returning the 65 seconds-hand to a predetermined position, of a locking device for holding the fly-back

mechanism inactive, a stop for engaging the watch-movement to stop the same, and a moving lever for operating the stop into engagement with the watch-movement and releasing 70 the locking device when moved in one direction, the return movement of the lever disengaging the stop from the watch-movement and restoring the locking device to its normal position.

8. In a watch, the combination with a seconds-hand mounted to be turned by the watch-movement or to turn independently thereof, and a fly-back mechanism for returning the seconds-hand to a predetermined position, of 80 a locking device for holding the fly-back mechanism inactive, and an operating-lever operatively connected with the locking device and provided with a stop for engaging the watch-movement to stop the same, said lever 85 when moved in one direction bringing the stop into engagement with the watch-movement and releasing the locking device, and when moved in the opposite direction disengaging the stop from the watch-movement and restoring the locking device to its normal position.

9. In a watch, the combination with a seconds-hand mounted to be turned by the watch-movement or to turn independently thereof, 95 and a heart-cam rigid with the seconds-hand, of a spring-pressed arm adapted to strike the cam to cause the seconds-hand to fly back to a predetermined position, a locking device for the said arm, and an operating-lever having 100 one end operatively connected with the locking device and provided with a stop for engaging the watch-movement to stop the same, said lever when moved in one direction bringing the stop into engagement with the watch-movement and releasing the locking device, and when moved in the opposite direction disengaging the stop from the watch-movement and restoring the locking device to its normal position.

10. In a watch, the combination with a seconds-hand mounted to be turned by the watch-movement or to turn independently thereof, and a heart-cam rigid with the seconds-hand, of a spring-pressed arm adapted to strike the 115 cam to cause the seconds-hand to fly back to a predetermined position, a link pivoted to the arm and provided with an L-shaped guideway, a fixed pin working in the guideway of the link, and an operating-lever having one 120 end operatively connected with the link and provided with a stop for engaging the watch-movement to stop the same.

11. In a watch, the combination with a seconds-hand mounted to be turned by the watch-movement or to turn independently thereof, 125 and a heart-cam rigid with the seconds-hand, of a spring-pressed arm adapted to strike the cam to cause the seconds-hand to fly back to a predetermined position, a link pivoted to 130 the arm and provided with an L-shaped guideway and with spaced projections, a pin work-

ing in the guideway of the link, and an operating-lever having at one end inclined faces extending between the projections of the link and provided with a stop for engaging the 5 watch-movement to stop the same.

12. In a watch, the combination with a stop and fly-back hand, of an operating-arm having a yielding stop arranged to engage a part of the clockwork during the movement of 10 said arm in one direction, and a fly-back mech-

anism arranged to be operated by the further movement of said arm in the same direction.

In testimony whereof I have signed my name to this specification in the presence of two subscribing witnesses.

SAM GOLDFADEN.
